(57) **CLAIM**

The ornamental design for an electronic cigarette as shown and described.

DESCRIPTION

FIG. 1 is a rear perspective view of an electronic cigarette, showing my new design;

FIG. 2 is a rear, top perspective view thereof;

FIG. 3 is a front perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings depict portions of the electronic cigarette that form no part of the claimed design. All unshaded tween solid and broken lines in FIG. 8 and FIG. 9 form no part thereof.
